[57] CLAIM

The ornamental design for gasoline pump, as shown and described.

DESCRIPTION

FIG. 1 is a front elevational view of a gasoline pump showing my new design, the rear being a mirror image thereto;

FIG. 2 is a left side elevational view thereof;

FIG. 3 is a right side elevational view thereof;

FIG. 4 is a top plan view thereof;

FIG. 5 is a bottom plan view thereof.
